PROCESS OF TREATING HYDROCARBONS

Harold M. Smith, Peter Grandone, and Harry T. Rall, Bartlesville, Okla.

Application August 19, 1932, Serial No. 629,734

21 Claims. (Cl. 196—10)

(Granted under the act of March 3, 1883, as amended April 30, 1928; 370 O. G. 757)

This invention described herein may be manufactured and used by or for the Government for Governmental purposes, without the payment to us of any royalty thereon.

5 This invention relates to improvements in processes for the thermal-decomposition of gaseous hydrocarbons such as occur in natural gas and the like.

One object of this invention is to provide an industrially feasible process for converting gaseous paraffin hydrocarbons, typified by methane, ethane, butane, propane and isobutane, either collectively or separately into products valuable as component motor fuels, solvents and organic 15 intermediates.

Another object of this invention is to provide a process by which the large volume of unsaturated aliphatic gases such as ethylene, propylene and acetylene heretofore to a large extent wasted in the thermal-decomposition of natural gases is almost completely converted to light oils and tars.

Another object of this invention is to provide a process wherein not only the amount of polymerization but also its course is restricted so that the ratio of carbon to hydrogen in the compounds comprising the tars is limited to a ratio of 1.4 or less.

Another object of this invention resides in the provision of a process wherein the gaseous hydrocarbons in the hydrogenizing chamber are subjected to such conditions that only hydrogenated derivatives of the hydrocarbons are formed.

35 Another object of this invention resides in the provision of a method for the thermal-decomposition of gaseous paraffin hydrocarbons wherein the polynuclear compounds are split up and hydrogenated to form hydrocarbons with only one aromatic or benzene ring.

Another object of this invention is to provide a process by means of which gaseous hydrocarbon or two or more carbon atoms are separated and used to enrich the raw intake gas, either 45 immediately previous to or after cracking.

With the foregoing objects outlined and with other objects in view, which will appear as the description proceeds, this invention consists in the novel features to be hereinafter described in detail and more particularly pointed out in the appended claims.

Briefly stated, this invention consists in treating gaseous paraffin hydrocarbons typified by methane, ethane, butane, propane and isobutane 55 with a diluent in the nature of an inert gas such

as nitrogen, heating said gases under pressure to a temperature just sufficient to break the carbon-to-carbon or carbonhydrogen bonds and with a sufficient velocity of the gas stream so that no secondary reactions occur in the reaction tube, 60 directing the gaseous mixture immediately into an unheated polymerizing chamber, passing the product, still in a vapor state over hydrogenating catalyst to either split the polynuclear compounds, hydrogenate unsaturated compounds, or 65 both, removing the liquid products formed, adding the gaseous hydrocarbons formed with two or more carbon atoms to the input gas and burning the residual methane and hydrogen to provide heat for the entire process.

The early development of new oil fields is usually accompanied by large quantities of natural gas and consequently the coincident production of this gas, rich in commercially valuable compounds, will continue as long as present day production methods are resorted to. At 75 the present time vast quantities of this gas are wasted by being blown into the air.

Research workers have accomplished a great deal in their efforts to overcome this loss by developing processes for converting the gaseous constituents of the natural gas into commercially valuable substances such as anti-knock motor fuel, wash oil, solvents and the like, but up to the present time their objective has not been fully 80 realized. This failure may be partially attributable to a lack of full regard for such factors as temperature, gas velocity, effect of pre-heating, size, heat conductivity and composition of the reaction tube, temperature effects on the 85 cracking gas, and type of flow, that is to say, streamline or turbulent, all of which, in the prevailing methods for the treatment of natural gas, unquestionably contribute to the production of undesirable hydrocarbons, usually classified as 90 tars and the waste of large volumes of unsaturated aliphatic gases, such as ethylene, propylene and acetylene.

It is therefore the aim and purpose of this invention to provide a simple, inexpensive process 100 which will overcome these defects, afford a more diversified utilization of hydrocarbon gases, especially natural gas, and effect a commercially practical process which will materially increase light oil yield.

Coming now to a more detailed discussion of the application of the process under consideration, the gaseous mixture to be processed, which may be natural gas, pressure still gases, oil gases, etc., preliminary to its passage to the cracking 110

tube is diluted with an inert gas preferably nitrogen. Experiments have shown that dilution with nitrogen up to 20 or 25 percent does not effect the desired yields of unsaturated hydrocarbon for light oils, but does decrease the amount and improve the character of the tar formed, thus nitrogen as a diluent has a two-fold effect in that it serves not only to restrict the amount of polymerization but also the course of said polymerization so that the ratio of carbon to hydrogen in the compounds comprising tar is much smaller. The carbon to hydrogen ratio being about 1.4 or less.

After dilution with nitrogen the raw gaseous mixture is directed to a reaction tube where the incoming gases diluted with nitrogen are heated as rapidly as possible to a temperature sufficient to crack the hydrocarbon molecules and form fragments or free radicals. This is best carried out at temperatures ranging between 700 and 1200° C. and with the gases flowing through the reaction tube with sufficient velocity and turbulence to avoid formation of light oils. Experiments have shown that with a gas of the following composition, methane 65.8%, ethane 3.7%, propane 1.9%, butane 1.0%, pentane and higher 0.4%, nitrogen and inerts 27.2%, the relation between temperature and contact time for the maximum production of unsaturated hydrocarbons is approximately given by the following equation:

$$\log_{10} T = 3.0164 - .0484 \theta$$

where T is the temperature in degrees centigrade and θ is the contact time in seconds. That contact time is of course inversely proportional to the rate of gas flow or velocity. This equation holds very well at atmospheric pressure, and experiments at pressures of six atmospheres do not indicate much deviation. It is obvious that every gas whose composition differs much from the example given will require a different equation, but the relation indicates very well the dependence of results upon the regulation of the gas velocity and temperature. The necessity for exact control of the gas velocity is also well illustrated by the following table showing the per cent ethylene obtained from the same gas mentioned above at 900° C. and atmospheric pressure, when the contact times are changed:

Contact time	Per cent ethylene
5.92 seconds	2.53
4.73 seconds	2.93
2.36 seconds	3.74
1.44 seconds	4.79
0.73 seconds	2.62
0.35 seconds	2.24

A similar relation will obtain under pressure, but, due to the reversibility of the reaction whereby ethylene is formed, higher temperatures are necessary to attain the same equilibrium point. During this step the nitrogen diluent assists in preventing the start of secondary reactions in the hot tube.

At this point it might be well to state that as a cracking tube, any alloy or refractory material or combination of these which can be used at high temperatures and pressures up to 100 pounds per square inch may be employed, provided that a large surface of iron or nickel is avoided. The reaction tube may be heated externally by electricity or by any other suitable means, but pref-

erably by the residue gas from the process. The hot gases now in a state of disintegration are next directed into a thermally insulated polymerizing chamber, preferably of the same material as the cracking tube, but of such dimensional relation to the cracking tube that the velocity of the gas stream is materially decreased. During this polymerization stage of the process, adequate and efficient heat control is very essential due to the exothermic character of the reaction, in order that the polymerization may be held within definite limits. This control is obtained by employing the available heat of the incoming gases, the exothermic heat of the polymerizing reactions, and the cooling effect of the raw gases which for this purpose may be by-passed from the source of supply through the polymerization chamber. These factors will serve to maintain the heat equilibrium desired, preferably between 500 and 700° C.

The nitrogen diluent is particularly advantageous in this part of the process by providing heat by convection, for the reaction and by its favorable action in restricting the polymerization reaction to the formation of light oils and tars of low carbon hydrogen ratio. Catalysts favorable to polymerization, such as active silica or active carbon, with or without deposited metals, may be employed during this polymerization stage but their use is not necessary.

As the next step to the process, the entire gaseous mixture, as it leaves the polymerizing chamber with all the light oil and tar in vapor state, is led over a series of hydrogenating catalysts suitably located in a hydrogenating chamber. This catalyst may consist of nickel, cobalt, mixtures of these metals with each other, or with metals such as molybdenum, chromium, mercury and thorium, and it may be mounted on either a support such as granular pumice, silica gel or active charcoal, or mixed with a material such as ground pumice unsupported. Experimental work has shown that catalysts of the type mentioned will bring about the desired reactions, but it is to be understood that the process is not to be restricted to this particular catalyst. To provide the requisite temperature conditions it is desirable to mount the hydrogenating chamber in a compartment formed in the flue of the furnace, so that when desirable the heated flue gases may be by-passed through the compartment. By utilizing the hydrogen previously evolved in the formation of light oil or tar, several different reactions may take place, depending upon the velocity of the gas stream, the temperature, the catalyst chosen and its concentration, all of which are determining factors in the extent of splitting and amount of hydrogenation.

For instance, at temperatures 100-300° C., most of the products in the hydrogenating chamber form hydrogenated derivatives. The tars which are ordinarily rather dark and viscous liquids are converted to hydrogenated polynuclear compounds with boiling points below 300° C. Naphthalene forms either tetra—or deca-hydro-naphthalene, depending on conditions; benzene is converted into cyclohexane; ethylene to ethane; and similarly all of the other hydrocarbons add more or less hydrogen. These reactions are exothermic and excess heat is removed by preheating all or a part of the input gas through a closed coil or other appropriate means.

At temperatures 300 to 600° C., destructive hydrogenation of the tars occur. This may be typified by the reaction of naphthalene, one of the

major constituents of the tar, which reacts as follows:

- 5 This reaction is endothermic and if more heat than is available in the gas is necessary all or a part of the flue gas may be by-passed through the compartment housing for the hydrogenating chamber. On the other hand, if there is excess heat, all or a part of the input gas may be pre-heated. Thus the total yield of light oil of a single nuclear structure is approximately doubled, since, under the best conditions, somewhat less tar than light oil is originally formed. A 10 considerable portion of hydrogen is removed from the residue gases, thus enhancing their heating value.

The whole of the gaseous mixture, consisting of fixed gases and vapors, is next passed into a 20 scrubbing tower or other device so operated that all of the polymerized liquids and gaseous compounds with more than one carbon atom are removed. Tetrahydronaphthalene, one of the products which may be produced by the low temperature hydrogenation, can be advantageously employed as a wash oil. The residue gases consisting of methane, hydrogen and nitrogen, may be used in several ways but preferably by providing heat for the cracking reaction. The entire process from the initial heating to the absorption of the light products should be carried out within a pressure range of 30-100 pounds.

The final step in the process is carried out by reducing the pressure to atmospheric and heating the absorbing agent whereby the volatile light oils, or mixtures of aromatic hydrocarbons, are recovered and the gaseous hydrocarbons of two or more carbon atoms are collected and returned to enrich the intake gas at the cracking furnace. 40 In the manner of carrying out the process where such products as tetrahydronaphthalene are formed, they will not be recovered with the volatile oils, but will accumulate with the wash liquid, and as that increases in amount, portions of it 45 may be heated sufficiently to distill off the desired product.

Manifestly various forms of apparatus may be employed to carry out the several steps of this invention but for the purpose of the present disclosure reference will be made to the embodiment 50 diagrammatically shown in the single figure of the accompanying drawing.

Referring more particularly to the drawing, the single figure diagrammatically shows partially in elevation, partially in section, an operative assembly of the several components of one form of apparatus which has been successfully resort- 55 ed to for the purpose of carrying into effect the principles of this invention.

Assuming the intake A connected to a source of hydrocarbon gas and intake B to the source of a diluent such as nitrogen, after the proper valve of the valve group C has been adjusted to mix the diluent with the hydrocarbon gas, the mixture flows through the line (5) into the upper end of reaction tube (6). Descending the branches of this tube the gases leave its lower end and entering line (6') flow into the upper end of the polymerization chamber (10). During its passage through the reaction tube (6) the gaseous mixture is subjected to a temperature ranging between 700 to 1200° C. The polymerization chamber (10) into which the gases flow after leaving reaction tube (6) is internally baffled and centrally positioned in an unheated insulated re-

action vessel (11). As the gases traverse the polymerization chamber (10) following the irregular course prescribed by the baffles, they are heated to a temperature of 500 to 700° C. Temperature control of the polymerization chamber is secured by by-passing a part or all of the input gases from the intakes A, B, through the line (12) into the bottom of reaction chamber (11), through this chamber and around the polymerization chamber (10) and then through upper end of chamber (11), line (12') back to line (5).

This flow of the input gases around the polymerizing chamber is regulated by means of thermo-electric devices (not shown). By-passing the gases in this manner not only maintains the proper temperature within the polymerization chamber but also enables preheating of the input gases when the occasion demands.

The cracked gases having been polymerized by their passage through the polymerization chamber (10), enter line (14) and passing through this line flow into the upper end of the hydrogenating chamber (15). Hydrogenating chamber (15) is located in a walled compartment D formed in the upper part of furnace E. A pair of flue valves 100 (19) and (20) permit the flue gases to be bypassed through compartment D for the purpose of controlling temperature conditions in the hydrogenating chamber as will be understood without further discussion. These valves are adapted to 105 be operated by thermo-electric devices (not shown). The gases entering the hydrogenating chamber (15) flow through said chamber over catalysts (16). At this point several reactions take place depending upon temperature conditions, the gas stream velocity, nature of the catalyst and its concentration, all of which are, as previously stated, determining factors in the extent of splitting and the amount of hydrogenation.

Leaving the hydrogenating chamber (15) the gases enter line (21) and flow into the upper end of heat exchanger (22). After being suitably cooled by their passage through the heat exchanger, the gases enter line (23) and flowing through the latter are directed into the lower end of pressure scrubbing tower (24), into which wash oil is sprayed from the nozzle (25). This nozzle is mounted in the upper end of the tower, and connected to a source of wash oil supply in a 115 manner hereinafter to be described. The wash oil sprayed into the scrubbing tower absorbs the liquid hydrocarbons and also gaseous hydrocarbons having two or more carbon atoms. The methane hydrogen and other fixed gases collecting in the upper end of the scrubbing tower enter line (26) through which they are directed into lines (26'), (27') and thence to burners (8) and (8').

Coming now to the final stage of this process 120 the enriched absorbent in the bottom of scrubbing tower (24) is directed via line (27) to coil (22') in heat exchanger (22) wherein it is heated by the incoming gases from line (21). Leaving the coil (22') it is directed via line (28') into heating coil (28) located in the base of the furnace and thence through line 30 into evaporating chamber (31).

The denuded wash oil collecting in the bottom of the evaporating chamber passes through line (42) into tank (43) containing the cooling coil 125 (44). From this tank through pump (45) and line (46) cool wash oil is returned to the spraying nozzle (25) in the upper end of scrubbing tower (24).

The gaseous hydrocarbons are removed from 130

the upper end of evaporating chamber (31) and directed into condenser (33) via line (32). The lower end of the condenser (33) connects with separator (35). The volatile light oils or mixtures of aromatic hydrocarbons collect in the separator (35) while the hydrocarbon gases having two or more carbon atoms are recycled through line (36), pump (37), line (38), and valves (39) and (40) to reaction tube (6) and/or polymerizing chamber (10) depending upon the exigencies of the situation.

The air for combustion in the burners is introduced through the inlet valve (47), recuperator (48), line (49), valve (50), and line (27'). Valve (51) provides for by-passing the methane and fixed gases from the top of the scrubbing tower (24) to any desired place. The valve (52) furnished another intake for extra fuel when the latter becomes necessary.

20 In conclusion, it is evident this invention by converting the undesirable tars into useful products and utilizing valuable constituents of the gases which in similar processes have been wasted, greatly improves the light oil yield and materially 25 widens the market for natural gas products.

Having described our invention, what we claim as new and wish to secure by Letters Patent is:

1. A process for the thermal decomposition of gaseous paraffin hydrocarbons consisting in heating the gases under pressure to a temperature just sufficient to crack the hydrocarbons and form fragments or free radicals, regulating the velocity and turbulence of the gas stream during this thermal treatment to prevent secondary reactions, directing the heated gases into a polymerizing chamber, limiting the polymerization reaction to a definite temperature range, removing the light oils and tar while still in a vapor state from the polymerizing chamber and passing them over a hydrogenating catalyst at a predetermined temperature and then extracting the liquid products formed.

2. A process for the thermal decomposition of gaseous paraffin hydrocarbons consisting in rapidly heating the gases under pressure to a temperature just sufficient to crack the hydrocarbons and form fragments or free radicals, controlling the velocity and turbulence of the gas stream during this treatment so as to prevent secondary reactions, directing the heated gases into a polymerizing chamber, limiting the polymerization reaction to a definite temperature range, removing the light oils and tars while still in a vapor state from the polymerizing chamber and passing them over a hydrogenating catalyst at a predetermined temperature, reducing the gas pressure to atmospheric and then extracting the liquid products formed.

3. A process for the thermal decomposition of gaseous paraffin hydrocarbons consisting in heating the gases under pressure to a temperature sufficient to crack the hydrocarbons and form fragments or free radicals, controlling the velocity and turbulence of the gas stream during this thermal treatment so as to prevent secondary reactions, directing the heated gases to a polymerizing chamber and materially reducing the velocity of gaseous flow, limiting the polymerization reaction to a definite temperature range, 70 moving the light oils and tar still in vapor state from the polymerizing chamber and passing them over a hydrogenating catalyst at a predetermined temperature, reducing the pressure of the gases to atmospheric and extracting the liquid products 75 formed.

4. A process for the thermal decomposition of gaseous paraffin hydrocarbons consisting in heating the gases under pressure to a temperature sufficient to crack the hydrocarbons and form fragments or free radicals, controlling the velocity and turbulence of the gas stream during this heating period to prevent secondary reactions, directing the heated gases into a polymerizing chamber where their flow is materially reduced, limiting the polymerization reaction to a temperature between 500-700° C., passing the light oils and tar still in a vapor state over a hydrogenating catalyst at a predetermined temperature and then removing the liquid products formed.

5. A process for the thermal decomposition of gaseous paraffin hydrocarbons consisting in heating the gases under pressure to a temperature between 700-1200° C., which is just sufficient to crack the hydrocarbons and form fragments or free radicals, controlling the velocity and turbulence of the gas stream during this thermal treatment so as to prevent secondary reactions, directing the heated gases to a polymerizing chamber, the dimensions of which are such as to materially reduce the gas flow, limiting the polymerization reaction to a definite temperature range, passing the light oils and tar still in a vapor state over a hydrogenating catalyst at a predetermined temperature and then removing the liquid products formed.

6. A process for the thermal decomposition of gaseous paraffin hydrocarbons, consisting in heating gases under pressure to a temperature within the temperature range of 700-1200° C., which is just sufficient to crack the hydrocarbons and form fragments or free radicals, controlling the velocity and turbulence of the gas stream to prevent secondary reactions, directing the heated gases into the polymerizing chamber, the dimensions of which are such as to materially reduce the gas flow, limiting polymerization reaction to a temperature between 500-700° C., passing the light oils and tar still in a vapor state over a hydrogenating catalyst at a predetermined temperature and then removing the liquid products formed.

7. A process for the thermal decomposition of gaseous paraffin hydrocarbons consisting in heating the gases under pressure to a temperature within the temperature range of 700-1200° C., which is just sufficient to crack the hydrocarbons and form free radicals, controlling the velocity and turbulence of the gas stream to prevent secondary reactions, directing the heated gases into a polymerizing chamber, whose dimensions are such as to materially decrease the gas flow, limiting the polymerization reaction to a temperature between 500-700° C., passing the light oils and tar still in a vapor state over a hydrogenating catalyst at a temperature between 100-300° C., and then removing the liquid products formed.

8. A process for the thermal decomposition of gaseous paraffin hydrocarbons consisting in heating the gases to be processed to a temperature just sufficient to crack the hydrocarbon and to form fragments or free radicals, restricting the pressure to a range of 1-100 pounds per square inch, directing the gas along an irregular path so as to impart sufficient flow and turbulences to the gas stream during this stage of the process to prevent secondary reactions, directing the heated gases into a polymerizing chamber, whose dimensions are such as to materially reduce the

- gas flow limiting the polymerization reaction to a definite temperature range, passing the light oils and tar still in a vapor state over a hydrogenating catalyst at a predetermined temperature and then removing the liquid products formed.

9. A process for the thermal decomposition of gaseous paraffin hydrocarbons consisting in heating the gases under pressure to a temperature between 700-1200° C., which is just sufficient to crack the hydrocarbons and form free radicals, controlling the velocity and turbulence of the gas stream to prevent secondary reactions, directing the heated gases into a polymerizing chamber, whose dimensions are such as to materially decrease the gas flow, limiting the polymerization reaction to a temperature between 500-700° C., passing the light oils and tar still in vapor state over a hydrogenating catalyst at a temperature between 300-600° C., and then removing the liquid products formed.

10. A process for the thermal decomposition of gaseous paraffin hydrocarbons consisting in diluting the gas to be treated with an inert gas, heating this mixture under pressure to a temperature just sufficient to crack the hydrocarbons and form fragments or free radicals, the velocity and turbulence of the gas stream during this thermal treatment being such as to prevent secondary reactions, directing the heated gases into the polymerizing chamber, limiting the polymerization reaction to a definite temperature range, removing the light oils and tar while still in a vapor state from the polymerizing chamber and passing them over a hydrogenating catalyst at a predetermined temperature and then extracting the liquid products formed.

11. A process for the thermal decomposition of gaseous paraffin hydrocarbons consisting in diluting the raw gas with a diluent in the nature of an inert gas such as nitrogen, heating the mixture under pressure to a temperature just sufficient to crack the hydrocarbons and form fragments or free radicals, the velocity and turbulence of the gas stream during this stage being such as to prevent secondary reactions, directing the heated gases into a polymerizing chamber, limiting the polymerization reaction to a definite temperature range, removing the light oils and tar while still in a vapor state from the polymerizing chamber and passing them over a hydrogenating catalyst at a predetermined temperature and then extracting the liquid products formed.

12. A process for the thermal decomposition of gaseous paraffin hydrocarbons consisting in diluting the raw gas with an inert diluent such as nitrogen, rapidly heating the gases under pressure to a temperature between 700-1200° C., which is just sufficient to crack the hydrocarbons and form fragments or free radicals, controlling the velocity and turbulence of the gas stream during this stage to prevent secondary reactions, so as to avoid formation of light oils and tar from unsaturated gases, directing the heated gases into a polymerizing chamber, the dimensions of which are such as to materially decrease the rate of gas flow, limiting polymerization reaction to a definite temperature range, removing the light oils and tar while still in a vapor state from the polymerizing chamber and passing them over a hydrogenating catalyst at a predetermined temperature and then extracting the liquid products formed.

13. A process for the thermal decomposition of gaseous paraffin hydrocarbons consisting in diluting the gases to be processed with an inert diluent such as nitrogen, heating the gases under pressure to a temperature between 700-1200° C., which is just sufficient to crack the hydrocarbons and form fragments or free radicals, controlling the velocity and turbulence of the gas stream during this thermal treatment so as to prevent secondary reactions, directing the hot gases, now in a state of disintegration to a polymerizing chamber, the dimensions of which are such as to effect a material reduction in the rate of gas flow, limiting the polymerization reaction to a temperature between 500-700° C., removing the light oils and tar while still in a vapor state from the polymerizing chamber and passing them over a hydrogenating catalyst at a predetermined temperature and then extracting the liquid products formed.

14. A process for the thermal decomposition of gaseous paraffin hydrocarbons consisting in diluting the gas or gases to be processed with an inert diluent in the nature of nitrogen, heating the gases under pressure to a temperature between 700-1200° C., which is just sufficient to crack the hydrocarbons and form fragments or free radicals, controlling the velocity and turbulence of the gas stream during this thermal treatment so as to prevent secondary reactions, directing the heated gases to a polymerizing chamber, the dimensions of which are such as to effect a material reduction in the rate of gas flow, limiting the polymerization reaction to a temperature between 500-700° C., removing the light oils and tar while still in a vapor state from the polymerizing chamber, and passing them over a hydrogenating catalyst at a temperature between 100-300° C., and then removing the liquid products formed.

15. A process for the thermal decomposition of gaseous paraffin hydrocarbons consisting in diluting the gas or gases to be processed with an inert diluent in the nature of nitrogen, heating the gases under pressure to a temperature between 700-1200° C., which is just sufficient to crack the hydrocarbons and form fragments or free radicals, controlling the velocity and turbulence of the gas stream during this thermal treatment so as to prevent secondary reactions, directing the heated gases to a polymerizing chamber wherein the dimensions of which are such as to effect a material reduction in the rate of gas flow, limiting the polymerization reaction to a temperature between 500-700° C., removing the light oils and tar while still in a vapor state from the polymerizing chamber, and passing them over a hydrogenating catalyst at a temperature between 300-600° C., and then removing the liquid products formed.

16. A process for the thermal decomposition of gaseous paraffin hydrocarbons consisting in diluting the gas or gases to be processed with an inert diluent such as nitrogen, heating the gases under pressure to a temperature sufficient to crack the hydrocarbons and form fragments or free radicals, controlling the velocity and turbulence of the gas stream during this heating period in accordance with the amount of splitting and dehydrogenation desired, directing the heated gases into a polymerizing chamber, the dimensions of which are such as to effect a material reduction in the rate of gas flow, limiting the polymerization reaction to a temperature between 700-1200° C., removing the light oils and tar while still in a vapor state from the polymerizing chamber and passing it over a hydrogenat-

ing catalyst under conditions to form hydrocarbons with only one aromatic or benzene ring and then removing the liquid products formed.

17. A process for the thermal decomposition of gaseous paraffin hydrocarbons consisting in diluting the gases to be processed with an inert diluent in the nature of nitrogen gas, heating the gaseous mixture under pressure to a temperature just sufficient to crack the hydrocarbons and form fragments or free radicals, regulating the velocity and turbulence of the flow of the gas stream during this thermal treatment to prevent secondary reactions, directing the hot gases now in a state of disintegration into a polymerizing chamber, limiting the polymerization reaction to a definite temperature range, removing the light oils and tar while still in a vapor state from the polymerizing chamber and passing them over a hydrogenating catalyst at a predetermined temperature, the concentration of the catalyst being varied depending upon the amount of hydrogenation desired, and then extracting the liquid products formed.

18. A process for the thermal decomposition of gaseous paraffin hydrocarbons consisting in diluting the gas to be processed with an inert diluent in the nature of nitrogen gas, heating this gaseous mixture under pressure to a temperature just sufficient to crack the hydrocarbons and form fragments or free radicals, regulating the velocity and turbulence of the gas stream during this thermal treatment to prevent secondary reactions, directing the hot disintegrated gases into a polymerizing chamber, limiting the polymerization reaction to a definite temperature range, removing the light oils and tar while still in a vapor state from the polymerizing chamber and passing them over a hydrogenating catalyst, maintaining the hydrogenating temperature within definite limits to form only hydrogenated derivatives and then extracting the liquid products formed.

19. A process for the thermal decomposition of gaseous paraffin hydrocarbons consisting in diluting the gas or gases to be processed with an inert diluent such as nitrogen gas, heating this mixture under pressure to a temperature just

sufficient to crack the hydrocarbons and form fragments or free radicals, regulating the velocity and turbulence of the gas stream to prevent secondary reactions, directing the heated gas to a polymerizing chamber, limiting the polymerization reaction to a definite temperature range, removing the light oils and tar from the polymerizing chamber while still in a vapor state and passing them over a hydrogenating catalyst at a predetermined temperature, extracting the liquid products formed and returning the hydrocarbons of two or more carbon atoms to the intake gas for enrichment purposes.

20. A process for the thermal decomposition of gaseous paraffin hydrocarbons consisting in diluting the gases to be processed with an inert diluent in the nature of nitrogen gas, heating the gas under pressure to a temperature just sufficient to crack the hydrocarbons and form fragments or free radicals, regulating the velocity and turbulence of the gas stream during this thermal treatment to prevent secondary reactions, directing the hot gases in a state of disintegration into a polymerizing chamber, limiting the polymerization reaction to a definite temperature range, removing the light oils and tar while still in a vapor state from the polymerizing chamber and passing them over a hydrogenating catalyst at a predetermined temperature, reducing the pressure of the gases to atmospheric and then extracting the liquid products formed.

21. A process for the thermal decomposition of gaseous paraffin hydrocarbons consisting in subjecting the gases under pressure to a temperature just sufficient to crack the hydrocarbons to form fragments or free radicals, regulating the velocity and turbulence of the gas stream during its thermal treatment to prevent secondary reactions, directing the heated gases into a polymerizing chamber, removing the light oils and tars while still in a vapor state from the polymerizing chamber and passing them over a hydrogenating catalyst, and then extracting the liquid products formed.
